RING SPINNING FRAME

Erich Reich, Aue, Germany, assignor to Ernst
Gessner Aktiengesellschaft, Aue (Saxony), a
German corporation

Application April 15, 1938, Serial No. 202,151
In Germany April 16, 1937

4 Claims. (Cl. 57—97)

This invention relates to ring spinning frames or machines and more particularly to the driving means for the calender rollers, drawing rollers and condenser bobbin rollers and to a method of adjusting the speeds of said rollers.

It occurs very often, more particularly with carded wool yarn, that small quantities have to be spun with different twists and drafts, whereby the speed of the slubbing or condensed sliver running off from the condenser bobbin has to be adjusted in accordance with the speed of the drawing rollers. In ring spinning frames for woollen spinning the twist and draft and the speed of the slubbing delivery are usually changed by exchanging gear wheels at three or four places. Of course, the machine has to be stopped for this purpose, which gives rise to waste of time and many accidents. Also, it is not possible to accurately predetermine or calculate the gears which are required, due to the frequent changes of the working method, the spinning material, its length of staple etc. occurring in woollen spinning. Therefore, it is required to find the adjustment required for the desired product by tests.

Moreover, in known machines of this kind, the draft, the twist and the condenser bobbin device have to be adjusted to suit the change speed gears, while any speed between two successive gear ratios cannot be adjusted at all, which is detrimental especially in the draft and condenser bobbin adjustment. Furthermore, in the known speed changing systems about sixty different change speed gear wheels are required for each machine the storage of which requires much space and attention.

It is the object of the invention to eliminate these defects of known ring spinning machines. To this end, I provide means for gradually and steplessly changing the driving speed of the calender rollers, drawing rollers and condenser bobbin rollers. Thus, it becomes possible to adjust the speed while the machine is in operation and without endangering the operator and to adjust the mutual ratio of the three speeds in accordance with the special features of the spinning material and of the yarn to be produced. Preferably the stepless change speed gears are arranged in series by driving the change speed gear for the calender rollers directly from the main shaft of the machine, while the change speed gear for the drawing cylinders is driven from the calender rollers and the change speed gear for the condenser bobbin rollers is driven from the drawing rollers.

In this manner the three speeds are interrelated so that when the speeds are to be changed, in the first instance only the change speed gear for the calender rollers has to be newly adjusted while the two other speeds change automatically in the same ratio. Only when it is found that the speeds of the drawing cylinders or of the condenser bobbin rollers require additional adjustment, the respective change speed gear is readjusted independently from the speed of the calender rollers.

It will be understood that instead of stepless gears separate variable speed motors may also be used, the speed, more particularly the starting speed of which is controlled from the main motor.

In order to facilitate the operation of my novel speed changing system, I provide means for indicating the speed of the different rollers. To this end, the various drives are coupled in suitable manner with indicators showing the number of revolutions of the spindle per minute, the twist per meter, the delivery per minute and the draft in percent. Thus, the operator can ascertain by a glance to the indicators whether the stepless adjustment of the various working speeds is correct or where readjustment is required. In this manner misadjustments can be recognized and corrected immediately, whereby time and material is saved.

The invention will be better understood by reference to the following detailed description in connection with the accompanying drawings showing by way of example and schematically some embodiments of the invention, viz—

Fig. 1 is a front view of the driving parts of a ring spinning frame, having the invention applied thereto, the parts not necessary for the understanding of the invention being omitted for the sake of simplicity.

Fig. 2 is a side elevation of the arrangement shown in Fig. 1.

Fig. 3 is a front view of a modified form of the driving parts.

Fig. 4 is a side elevation of the arrangement shown in Fig. 3.

Fig. 5 is a view, in larger scale, of the change speed gear for the condenser bobbin rollers, and

Fig. 6 is a plan view of the gear shown in Fig. 5.

Similar reference numerals denote similar parts throughout the different figures.

Referring now to the drawings in greater detail, there is shown a machine frame 1 in which the pairs of calender rollers 2, the pairs of draw-

ing rollers 9 and the condenser bobbin roller 10 are mounted.

The calender rollers 8 are driven by a stepless speed change gear 11 which is driven by a roller chain 13 from the main shaft 12 of the machine and controlled as to its speed ratio by a hand wheel 14.

A similar stepless change speed gear is provided at 15 for the drawing cylinders 9, driven, by 10 a roller chain 16, from the calender roller 8 and controlled by a hand wheel 17. While a great number of stepless change speed gears are known in the art, comprising, for example, friction wheels and discs the relative positions of which 15 are adjusted so as to change the gear ratio, one form of a stepless change speed gear is shown schematically in Figures 5 and 6 as inserted between the drawing cylinders 9 and the condenser bobbin roller 10. A V-belt pulley 18 is fast on 20 the shaft 19 of the drawing cylinders 9 and connected, by a V-belt 20, with an adjustable V-belt pulley 21 which in turn drives the condenser bobbin roller 10 and by adjustment of its adjustable portion 21' renders it possible to adjust the 25 speed ratio between the rollers 9 and 10.

As will be seen from Figures 5 and 6, the adjustable portion 21' of the pulley 21 is slidably mounted on its shaft and acted upon, at its center point 21'', by an arm 50 of an offset bell crank 30 lever 50, 51 pivoted at 52 and operatively connected by its arm 51 to the inner end of a threaded spindle 22' on which the hand wheel 22 is fixedly mounted.

Thus by moving the portion 21' more or less 35 towards the portion 21 of the pulley, the diameter of the running face on which the belt 20 runs and thus the gear ratio can be steplessly and gradually changed. From the pulley 21 the rollers 10 or 40 their gear wheels 10' respectively are driven in known manner through gear wheels 53 and 54 (shown in dotted lines in Fig. 5) and act upon the bobbins 23.

It will be understood that similar change speed gears as shown in Figs. 5 and 6 or any other suitable type of stepless change speed gear may be arranged in the gear boxes 11 and 15 in Figs. 1 to 4.

The operation will now be briefly described. The slubbing or roving coming from the bobbin 50 23 passes between the drawing cylinders 9, is twisted by the revolving or twist tube 24 which in the manner known per se may be driven at different speeds, and passes between the calender rollers 8 to the spindle 25, being drawn between 55 the rollers 9 and 8. The amount of draft depends substantially on the relative speeds between the cylinders 9 and 8.

The spindle 25 is driven in the usual manner from the drum 31 which in turn is driven in 60 known manner with adjustable speed from the main shaft 12.

It will thus be understood that when adjusting the speed of the calender rollers 8 by means of the hand wheel 14, the speed of the drawing cylinders 9 and of the drum 31 is also changed, because the change speed gears are arranged in series. Where only a change of the yarn twist is required, merely the gear ratio at 11 has to be readjusted, by means of the hand wheel 14, 70 while, where the draft is also intended to be changed, the gear ratio at 15 has also to be readjusted, by means of the hand wheel 17, whereby the speed of the condenser bobbin is automatically changed at the same time. (The hand wheel 17 has been shown in Figs. 1 and 3 as

arranged above hand wheel 14 for the sake of a better survey, but actually these two hand wheels are arranged side by side, as shown in Fig. 2.) Only in case the slubbing delivery should be found to be too fast or too slow the speed of the drum 10 has to be readjusted additionally by means of the hand wheel 22. All of these adjusting operations can be carried out while the machine is running and the adjustment of the change speed gears can be supervised at indicators 33, 34, 35, 36 which will be hereinafter described.

In the arrangement shown in Figs. 3 and 4, the stepless change speed gear 11 for the calender rollers 8 is coaxially arranged and connected with the main driving shaft 12. From the shaft 28 of this gear the speed of which is changed by the hand wheel 14, there are driven the calender cylinders 8, by a roller chain drive 29, and the drawing cylinders 9, by a roller chain drive 30 and an inserted change speed gear 15. The remaining parts are as shown and described with reference to Figs. 1 and 2. The adjustment of the change speed gears is indicated by indicators 26 and 27 which are constructed and operatively connected with the respective shafts in the manner known per se.

In order to facilitate the control of the machine, I may provide additional indicators showing not only the adjusted positions of the change speed gears but the actual spinning data determining the spinning operation. For this purpose four indicators 33, 34, 35, 36 are shown in Fig. 2 arranged on the switchboard 32 above the hand wheels 14 and 17, indicating said spinning data, viz—indicator 33, the revolution number of the spindle per minute, indicator 34, the twist per meter, indicator 35, the delivery per minute and indicator 36, the draft in percent. The indicator 33 is coupled with the drum 31 and the indicator 35 is coupled with the drive for the calender roller 8, while the indicator 34 is a differential or divisional indicator inserted between the indicators 33 and 35 and indicating the ratio

$$\frac{\text{spindle speed}}{\text{spinning speed}}$$

that is to say the twist. The indicator 36 in turn is inserted between the drive of the drawing cylinders 9 and the drive of the calender cylinders 8 and indicates the ratio

$$\frac{\text{drawing speed}}{\text{delivery speed}}$$

that is to say the draft in percent. Divisional indicators indicating the ratio of two speeds are known per se and need not be described here in detail.

In this manner the spinner, immediately he operates the hand wheels 14 and 17, is enabled to supervise the reaction of the spinning operation and data to the adjustment and thus he can correct the adjustment before damages occur.

It will be understood that it is within the purview of the invention to drive the indicators mechanically, electrically, hydraulically or in any other suitable manner and the instruments may be constructed in any suitable manner as known per se.

While I have herein shown and described certain preferred embodiments of my invention, I 70 wish it to be understood that I do not confine myself to all the precise details herein set forth by way of illustration, as modification and variation may be made without departing from the spirit of the invention or exceeding the scope 75

of the appended claims. More particularly, in view of the great number of different types of stepless speed changing means and ring spinning machines, considerable constructional changes 5 may be effected without departing from the scope of the invention. For example, separate variable speed motors may be used for driving the three said types of rollers (calender rollers, drawing rollers and condenser bobbin rollers) individually. 10 In this case, the casings 11 and 15 would represent the respective variable speed motors and the cone belt pulley 21 would be replaced by another variable speed motor. The speeds, especially the starting speeds of these motors will have to be 15 controlled from the main motor.

I claim:

1. A ring-spinning machine of the character described, having a spindle and its drive, calender rollers, drawing rollers and condenser bobbin 20 rollers, a variable speed transmission for driving said calender rollers, a similar transmission each for said drawing and said condenser bobbin rollers, and means for driving said variable speed transmissions in series to interrelate the speeds 25 of said devices, to permit speed regulation of the several sets of rollers during the operation of the machine, and to adjust a desired speed ratio between the roller sets and the spindle when one or several of said transmissions are varied. 30 2. A ring-spinning machine of the character described, having a spindle and its drive, calender rollers, drawing rollers and condenser bobbin rollers, a variable speed motor for each of said roller sets, a main motor arranged to control the 35 speed of said variable speed motors, to permit speed regulation of the several sets of rollers during the operation of the machine, and to adjust a desired speed ratio between the speeds of the several roller sets and the spindle when the speeds 40 of one or several of said motors are varied.

3. A ring-spinning machine of the character described, having a spindle and its drive, calender rollers, drawing rollers and condenser bobbin rollers, a variable speed transmission for driving said calender rollers, a similar transmission each 5 for said drawing and said condenser bobbin rollers, means for driving said variable speed transmissions in series to interrelate the speeds of said devices, to permit speed regulation of the several sets of rollers during the operation of the machine, and to adjust a desired speed ratio between the roller sets and the spindle when one or several of said transmissions are varied, and means for individually indicating the spindle 10 speed, the twist, the delivery and the draft of the 15 thread.

4. A ring-spinning machine of the character described, having a spindle and its drive, calender rollers, drawing rollers and condenser bobbin rollers, a variable speed transmission for driving 20 said calender rollers, a similar transmission each for said drawing and said condenser bobbin rollers, means for driving said variable speed transmissions in series to interrelate the speeds of said 25 devices, to permit speed regulation of the several sets of rollers during the operation of the machine, and to adjust a desired speed ratio between the roller sets and the spindle when one or several of said transmissions are varied, and an indicator connected with the spindle drive for 30 indicating the spindle revolutions per minute, a second indicator connected with the calender rollers for indicating the unit length delivery per minute, a third indicator differentially connected between the first and second indicators to indicate 35 the twist of the thread, and a fourth indicator differentially connected between the drawing roller and the calender roller drive for indicating the draft in per cent.

ERICH REICH. 40
